UNITED STATES PATENT OFFICE.

ARTHUR A. JOHNSON, OF WASHINGTON, DISTRICT OF COLUMBIA, ASSIGNOR TO
UNDERWOOD TYPEWRITER COMPANY, OF NEW YORK, N. Y., A CORPORATION
OF DELAWARE.

MANIFOLDING.

Application filed September 11, 1920. Serial No. 409,626.

To all whom it may concern:

Be it known that I, ARTHUR A. JOHNSON, a citizen of the United States, and a resident of the city of Washington in the District 5 of Columbia, have invented new and useful Improvements in Manifolding, of which the following is a specification.

This invention relates to manifolding and more particularly to the provision of means 10 whereby the creeping of separate superposed webs is obviated.

In manifolding typewriting machines and other machines it has been found that the webs, if made integral, will be maintained in 15 proper superposed relation to one another, so that the writing lines on the upper-most sheet will properly register with the writing line on the lower sheets. That it is unnecessary to provide additional registering means 20 for such a web, a fan-folded web for instance, is well known in the art. This, it is believed, is due to the fact that the webs are connected at one side edge and thus pass around or between cylindrical members, such 25 as the platen and feed rolls of a rotary platen typewriting machine, as a single thick sheet would.

A typewriting machine capable of accommodating such fan-folded webs is illustrated 30 in the patent to Smith, No. 1,177,546, granted March 27, 1916. In this patented machine, the carbon sheets are interposed between the folds of the web and are carried by carbon arms mounted on a reciprocating carriage, 35 so that, after a form has been written upon and the platen swung upwardly sufficiently to permit it, the carbon sheets are shifted with respect to the web to the proper position with respect to the next form.

40 It is sometimes desired that the webs be separate from one another in the form of separate continuous strips and in this case usually some means must be provided for re-aligning the webs after each form is fed or 45 during the feeding thereof.

The means of the present invention for obviating the creeping of the separate webs comprises a fan-folded fabric for embracing the separate webs of the pack. This folded 50 fabric itself being fed without creeping, naturally prevents the creeping of the separate webs which are embraced thereby. This folded fabric of the present invention may also carry the carbon for making carbon impressions on the separate superposed webs.

If this is done the surface of each part of the folded fabric that lies directly above a worksheet is provided with the usual manifolding material.

A feature of this invention is also the 60 provision of means by which the folded fabric carbon sheet may be attached to the reciprocating carbon holder. This means may comprise a tongue on each leaf of the folded carbon sheet which tongue may be 65 wrapped around the usual carbon holding arm to be secured thereto by the usual clamp.

The folded carbon sheet is preferably fan-folded.

An additional fold may be provided upon 70 the folded carbon sheet for the purpose of underlying the bottom web to include said web in its embrace.

The top web may under some circumstances be excluded from the embrace of the 75 folded carbon sheet since the creeping between the other webs held in a pack by the folded carbon sheet and the top web would be slight, if any. Under some circumstances, however, it will be desirable to form 80 the uppermost or "original" web integral with the web immediately below it and to have this lower web included in the embrace of the folded carbon sheet. If this is done, the web comprising the "original" web and 85 the "first copy" will have its fibres ruptured or will be provided with perforations at the fold to facilitate separation of the two parts thereof.

Other features and advantages will here- 90 inafter appear.

In the accompanying drawings;

Fig. 1, is a side view showing, diagrammatically, a fan-fold typewriting machine.

Fig. 2, is a perspective view showing part 95 of the fan-folded carbon sheet of this invention with the separate webs and the folded web.

Figure 3, is a view of the carbon sheet before folding.

Fig. 4, is a perspective view showing the graduated tongues of the fan-folded carbon sheet.

Fig. 5, is a side view of the fan-folded carbon sheet showing the carbon holding 105 arms in section.

Fig. 6 is a view in cross-section of the folded carbon sheet and the webs inserted between the leaves of the carbon sheet.

In the Underwood fan-fold typewriter, a 110

platen 10, is mounted to swing upwardly and forwardly in order to permit the operator to straighten the course of the web or webs, so that the carbon sheet or sheets may be moved 5 to a new position with respect to the web or webs, by the rearward movement of a reciprocatory carriage 11, mounted to slide on a frame 12, which forms part of the typewriter carriage. The carriage 12 is provided with 10 carbon carrying arms 13, each of which is provided with a carbon clamp 14. The mechanism, just referred to, may be substantially the same as that disclosed in said patent to Smith.

15 According to the present invention, the separate webs 15, and the web 16, are embraced by a fan-folded carbon sheet, designated generally by the numeral 17. This carbon sheet comprises a part 18, a part 19, 20 and a part 20 having carbonized faces 18^a, 19^a, and 20^a, respectively, for the webs 16, 15, and 15, respectively. The folded carbon sheet 17 is provided with an additional leaf 21 which underlies the lowermost web 15 and 25 causes said web to be embraced between it and the part 20 of the carbon sheet. This part 21, being directly against the platen, when in the machine, is not carbonized on either surface. The uppermost web 15, is 30 embraced between the part 20, and the part 19, while the web 16, is embraced between the part 19 and the part 18.

It will be seen that the separate webs are 35 embraced by the folded carbon sheet and that they are thus held against creeping.

The original web 22 may under some circumstances be a separate web since the creep between the webs held in a pack by the carbon sheet 17 and the web 22 would be 40 slight if any. Under other circumstances, however, and as shown in the drawings the web 22 and the web 16 are made integral and are connected at 23. Thus it will be seen that the web 16 being held in the embrace of the 45 folded carbon sheet, itself holds the web 22 against creeping. The folded web 16—22 is provided with a line of perforations 24 by means of which the parts 16—22 may be separated if desired. Each leaf of the folded 50 carbon sheet 17 is provided with a tongue 25 by means of which the carbon sheet is connected to the reciprocatory carriage 11. Each of these tongues 25 is wrapped about a carbon holding arm 13 and secured in place 55 on said arm by a clamp 14.

The tongues 25, are uncoated with carbon and are graduated in length, as shown in Fig. 4 or as shown in Fig. 5, to enable the use of carbon holding arms arranged as 60 shown in Fig. 4 or Fig. 5, which show the carbon arms in stepped relation. Fig. 3 shows the sheet 17 before folding, stripes being formed by the successive carbonized and uncarbonized portions.

In operation, the platen 10 is swung up-

wardly from the full-line position to the dotted-line position on Fig. 1, as more fully disclosed in said Smith patent, and the webs and carbon sheet, after being properly aligned, are placed around the platen of the typewriting machine in the usual manner and the platen 10 is restored to its normal position. After the "forms" are written upon, by the types 26 on type-bars 27, the leading edges of the webs which are slightly 75 in advance of the carbon sheet, are grasped and firmly held by the hand of the operator. The platen is then swung upwardly to permit the operator to straighten the webs, the carbon sheet is shifted to a new position and the leading edges of the webs are brought to a suitable gage. The platen is then returned to normal position where it 80 grips the carbon sheet and webs between it and the usual feed rolls, not shown; the webs 85 being held firmly by the operator during the entire operation.

Variations may be resorted to within the scope of my invention and portions thereof may be used without others.

Having thus described my invention, I claim:

1. A manifolding assemblage comprising, a fan-folded carbon sheet and a plurality of separate work-sheets embraced by said carbon sheet.

2. A manifolding assemblage comprising, a folded fabric, and a plurality of separate work-webs embraced by said folded fabric, whereby creeping between the work-webs 100 will be prevented when the assemblage is fed around the cylindrical platen of a typewriting machine.

3. A manifolding assemblage comprising, a fan-folding fabric, a plurality of separate work-webs embraced by said fan-fold fabric, and a folded work-web having one leaf embraced by the fan-folded fabric, whereby creeping between the work-webs will be prevented when the assemblage is fed around 110 the cylindrical platen of a typewriting machine.

4. A manifolding assemblage comprising, a fan-folded carbonized sheet, a plurality of separate webs embraced by said fan-folded carbonized sheet, and a folded work-sheet having one leaf embraced by the fan-folded carbonized sheet.

5. A manifolding assemblage comprising, a folded fabric and a plurality of work-sheets embraced by said folded fabric, said folded fabric having a carbonized face on each of the leaves thereof that faces the working face of a work-sheet.

6. A manifolding assemblage comprising, a folded fabric and a plurality of work-sheets embraced by said folded fabric; said folded fabric having a carbonized face on each of the leaves thereof that faces the working face of a work-sheet and having an

uncarbonized leaf formed integral with the folded fabric embracing the lowermost work-sheet.

7. A sheet for use in a typewriting machine, divided into stripes of substantially the same width, alternate stripes being carbonized on the opposite faces of the sheet so that, when the latter is folded along the lines of division between the stripes, the carbonized faces of the stripes will face in the same direction, said stripes having at one end of the sheet tongues for attaching the same to the blades of a carbon-sheet-carrier.

8. A manifolding assemblage comprising, a plurality of separate continuous webs and a plurality of carbon leaves, each leaf connected to an adjacent leaf at one side edge, said connected carbon leaves embracing the separate webs to hold the same from creeping.

9. A manifolding assemblage comprising a plurality of separate continuous webs and a longitudinally folded fabric for embracing said webs to prevent the creeping of the webs relative to each other and longitudinally of said fabric.

10. A sheet for use in a typewriting machine, divided into an even number of

stripes of substantially the same width, alternate stripes, with the exception of one at one side of the sheet, being carbonized on the opposite faces of the sheet so that, when the latter is folded along the lines of division between the stripes, the carbonized faces of the stripes will face in the same direction, 35 and the carbonized face of the last stripe will be covered by the uncarbonized stripe, said stripes having at one end of the sheet tongues for attaching the same to the blades of a carbon-sheet-carrier. 40

11. A sheet for use in a typewriting machine, divided into stripes of substantially the same width, alternate stripes being carbonized on the opposite faces of the sheet so that, when the latter is folded along the 45 lines of division between the stripes, the carbonized faces of the stripes will face in the same direction, said stripes having at their ends tongues graduated in length to correspond to the relative spacing of the carbon-clip blades of a carbon-carrier to which they are to be attached. 50

In testimony whereof, I have signed my name to this specification.

ARTHUR A. JOHNSON.
